UNITED STATES PATENT OFFICE.

EDWARD G. CARR, OF CHICAGO, ILLINOIS.

RAILROAD VEHICLE.

Application filed December 26, 1924. Serial No. 758,060.

This invention relates to railroad vehicles, and the object of the invention is to improve the construction and operation of railroad vehicles in the manner to be hereinafter described and claimed.

Referring to the drawings, which accompany this specification and form a part hereof, which drawings illustrate an embodiment of this invention, and on which drawings the same reference characters are used to designate the same parts wherever they may appear in each of the several views, Fig. 1 is a side elevation of a railroad vehicle; Fig. 2 is a plan view of the railroad vehicle shown by Fig. 1, parts being broken away; and Fig. 3 is an elevation of a part of a railroad vehicle.

Referring to the drawings, the reference numeral 1 designates a railroad vehicle designed and intended to operate upon the rails of a railroad track 2.

All details of construction, which are not necessary for a complete understanding of this invention, such as car couplings, etc., have been omitted for the sake of simplicity of illustration and description.

The railroad vehicle is illustrated as adapted to be supported on the rails of a railroad track by wheels 3, 4, 5, 6, 7, 8, 9, and 10, and the wheels are illustrated as connected in pairs by axles 11, 12, 13, and 14, according to the common method of construction of car wheels and axles in common use. At each end of each axle is a journal box 15, and these journal boxes are preferably designed to contain antifriction bearings 15^a, preferably of the roller type, although other types of bearings can be used if considered advisable. The drawings illustrate end thrust members 16 as secured to the journal boxes 15 by bolts 17. Springs 18, 19, 20, and 21, which are illustrated by the drawings as bowed laminated springs, are secured to the journal boxes 15 to form four-wheel trucks or trolleys, as clearly illustrated by the drawings. These springs may be secured to the journal boxes 15 in any suitable manner, as, for example, being passed between overhanging lugs 22, with the lowermost leaves of the springs secured to the journal boxes by bolts 23, as clearly shown by Fig. 1 and Fig. 2 of the drawings. A bolster 24 is illustrated as secured to the springs 18 and 19, and a bolster 25 is illustrated by the drawings as secured to the springs 20 and 21, with the trucks or trolleys pivotally connected with the superstructure of the vehicle by king pins 26 and 27.

The springs 18, 19, 20, and 21 are illustrated as laminated springs for the reason that laminated springs will ordinarily be employed, but each spring might consist of a single leaf if the superstructure of the vehicle, including the load carried by the vehicle, is light enough to warrant such a construction.

Supports 28 and 29 are secured to the vehicle and extend in close enough proximity to the tracks so that they will strike the tracks and support the vehicle before a dangerous pressure is exerted upon the bearings in the journal boxes. These supports will also prevent the flexing of the springs to a dangerous extent and will support the vehicle in case of derailment. Railroad vehicle axles are hardened at places of contact with bearings and roller bearings are also hardened. The object of the hardening is to prevent distortion under pressure and to minimize wear. Unfortunately, extreme hardness and toughness do not co-exist, and it is a principal object of this invention to prevent dangerous breaking or crushing stresses being imposed upon the bearings as the result of joltings of the vehicle whether due to rough track conditions or other causes. The supports 28 and 29 are primarily intended to strike the rails of the track, under severe joltings, and thus relieve the pressures exerted by the springs, through the journal boxes, upon the bearings. The supports 28 and 29 can be, as a matter of convenience in construction, connected to the springs and bolsters, as illustrated by the drawings, and they may consist of channel irons 30 with their webs placed vertically and secured, by rivets for example, to upper plates 31 and lower plates 32. Wooden planks 33 may be secured to the lower plates of the supports as readily replaceable wearing members, and the supports may be secured to the springs by bolts 34 and clips 35.

Referring, now, to Fig. 3 of the drawings, the reference numeral 1 designates a railroad vehicle generally, 36 and 37 wheels, 38 and 39 springs, 40 and 41 journal boxes, 40^a and 41^a antifriction bearings of the roller type, 42 and 43 end thrust members secured to the journal boxes 40 and 41 by bolts 44 and 45. The journal boxes 40 and 41 are il-

illustrated as formed with upper projections 46 and lower projections 47 for spring bolts 48 and 49. The longest leaves of the springs 38 and 39 are bent around the spring bolts, 5 in the ordinary manner of securing springs to spring bolts, which results in the springs being pivotally connected to the journal boxes and prevents a bending strain upon the springs of the character caused by the 10 overhanging lugs 22 and bolts 23 in the construction shown by Figs. 1 and 2 of the drawings. The construction shown by Fig. 15 of the drawings also tends to maintain the journal boxes in the same positions relative to the axles when the springs lengthen or shorten with vertical movements of the vehicle, whereas, with the construction shown by Figs. 1 and 2 of the drawings, the tendency is to oscillate the journal boxes about 20 the axles as the springs lengthen and shorten with vertical movements of the vehicle. There is, however, an important difference in principle of construction and in principle of operation between the construction shown by Figs. 1 and 2 of the drawings and the construction shown by Fig. 3 of the drawings in case the vehicle is to be self-propelled by a motor and motion transmitting mechanism to an axle, sprocket chain 25 drive and sprocket wheel on an axle, for example, which are not shown by the drawings for the reason that such mechanism is well known. Referring to Figs. 1 and 2 of the drawings, it will be noticed that any 30 power applied to an axle, other than a pure torque, will tend to displace the axle and bend the single springs. Referring, now, to Fig. 3 of the drawings, it will be noticed that any tendency of power means to displace an axle longitudinally will be offset, 35 resisted and prevented, because the axles are located between the springs 38 and 39.

Where double springs are used, I prefer to secure the springs together so that their 40 action will be the same as the action of a single spring, as distinguished from a construction in which one spring takes the load in the first instance and additional spring resistance being brought into 45 play by another spring, as is common in the construction of the spring supports for railroad cars. When I refer to railroad cars, I mean to include street cars and the like, as well as cars used on steam operated railroads. By having such springs connected, 50 as stated, and is illustrated by Fig. 3 of the drawings, the tendency to bend the springs or cause them to separate, when power is applied to an axle or wheels to propel the 55 car, is minimized. The springs may be secured together by bolts 50, which pass through plates 51 and 52 and clips 53. Channel irons 54 and 55, with their webs placed vertically, may be secured by rivets 60 to the plates 51 and 52 to form spacers be-

tween the springs and to afford common abutting means against which the springs can be seated by means of the bolts 50 to secure the springs together and to compel them to act as a single spring. A support 56, which is illustrated by the drawings as an I-beam, may be secured below the lowermost springs 39 for the same purpose as the supports 28 and 29 hereinbefore described. The support, or I-beam, 56 may be secured 70 to the vehicle in any suitable manner; Fig. 3 of the drawings illustrates this support as riveted to a plate 57, which is supported by bolts 50 underneath the lower springs 39. Fig. 3 of the drawings also illustrates a bolster 80 58 of the same construction as the bolsters 24 and 25 illustrated by Figs. 1 and 2 of the drawings.

It will, of course, be understood that Fig. 3 of the drawings illustrates a part only of a railroad vehicle and that this figure of the drawings illustrates only one side of a four-wheel truck or trolley, for the reason that the construction of the truck or trolley with two springs on each side can be readily understood from an inspection of Figs. 1 and 2 of the drawings and the description of the constructions hereinbefore made.

As the supports may, at times, be moving, for brief periods, in close proximity to the rails of the track, or may even be actually in contact with the rails of the track, the track contacting parts of the supports may be beveled or curved upwardly at their edges in the directions of movement of the vehicle, as indicated by the reference character 59, so that the supports will ride over an upwardly projecting butt of a rail, and not be stopped thereby.

The supports 28, 29, and 59, if not relied upon for supporting the vehicle in case of derailment, need not be arranged to contact with the rails, but can be arranged to contact with the axles inside of the car wheels as indicated in dotted lines by the reference numerals 60 and 61 on Fig. 1 of the drawings. With such a construction the bumps and jolts of the vehicle will be transmitted to the axles and so distribute the load on the bearing outside of a wheel and on the axle inside of a wheel as to avoid the damage which might be done to the bearing in case no support or supports were provided to relieve the bearings from excessive stresses.

The operation of the railroad vehicle will be readily understood from the foregoing description. If the vehicle is to be used as a car, it will be coupled by a coupling or couplings, not shown, to some kind of a locomotive and may form a part of a train of similar cars, although, of course, it can be coupled in a train with cars of other constructions. If the vehicle is intended to be a locomotive or self-propelled vehicle, it

will, of course, be provided with the necessary propelling mechanism, and may also be used to carry a load. The vehicle is specially adapted to temporary tracks either 5 standard gauge, or narrow gauge, contractors' tracks for example, and such tracks are usually rough tracks with curves which are of short radii and not banked so that the rolling stock is subjected to exceptionally severe conditions of use. When the vehicle lurches sideways on a curve, the lurch being outward, the springs spread the outside ends of the axles apart increasing the wheel base while the inside ends of the 10 same axles are pulled together decreasing the wheel base, with the result that the vehicle will take a curve more easily than as though such movements of the axles did not take place.

20 It will also be apparent that my improved construction reduces the weight of railroad vehicles by the elimination of parts which are ordinarily used in the construction of such vehicles; that the wear and binding 25 of journal boxes, when confined in pedestals, is obviated; and that the springs are unrestrained in their actions and do not have rubbing contact with parts of a truck or trolley.

30 The spring construction and arrangement shown by Fig. 3 of the drawings is also of special advantage when ordinary brakes and brake rigging, not shown, are used, for the reason that the pull of the brakes or 35 the brake rigging does not tend to displace the axles and bend the springs, and the same advantage exists if an obstruction is struck by a wheel or wheels.

40 What I claim is:

1. The combination in a railroad vehicle,

of axles with wheels thereon, journal boxes upon the axles, bearings interposed between the journal boxes and the axles, springs connected to journal boxes whereby pressure is transmitted through the journal 45 boxes and bearings to the axles, a bolster to which said springs are secured, and a support secured to the bolster so as to rise and fall therewith to limit the pressure exerted by the springs upon bearings and 50 also adapted to support the vehicle in case of derailment.

2. In mechanism of the class described, a trolley having wheels, rails on which the wheels of said trolley rest, yieldable means 55 supporting the trolley upon said wheels whereby the trolley may move downward with respect to said wheels when a load is placed on the trolley in excess of the sustaining capacity of said yieldable means, and means on the trolley normally spaced from said rails adapted to engage the latter when the trolley is moved downward with respect to said wheels to relieve the wheels 60 of excess load.

3. In mechanism of the class described, a wheeled trolley including a trolley frame, yieldable means supporting said frame upon said wheels whereby the frame may move 65 downward with respect to said wheels when a load is placed on the frame in excess of the sustaining capacity of said yieldable means, and means on said frame adapted to engage a downwardly immovable abutment when the frame is moved downwardly 70 with respect to said wheels to relieve the wheels of excess load.

In witness whereof I hereto affix my signature.

EDWARD G. CARR.
